(57) **CLAIM**

The ornamental design for a connector for a centrifuge balance bag, as shown and described.

DESCRIPTION

FIG. 1 is a perspective view of the connector for a centrifuge balance bag showing the new design;

FIG. 2 is a front elevational view thereof;

FIG. 3 is a back elevational view thereof;

FIG. 4 is a top plan view thereof;

FIG. 5 is a bottom plan view thereof;

FIG. 6 is a side elevational view thereof; and,

FIG. 7 is another side elevational view thereof.

The centrifuge balance bag is shown in broken lines to show environment for illustrative purposes only, and forms no part of the claimed design.
